Primary Examiner — Darlington Ly*Assistant Examiner* — Nasim Abdulaziz Ali(74) *Attorney, Agent, or Firm* — McCormick, Paulding & Huber PLLC(57) **CLAIM**

The ornamental design for a hydraulic steering unit, substantially as shown and described.

DESCRIPTION

FIG. 1 is a front, right side and top perspective view of the hydraulic steering unit comprising new, original, and ornamental design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines show portions of the hydraulic steering unit that form no part of the claimed design.
